DESIGN.

E. F. CURTIS,
WOVEN FABRIC OR SIMILAR ARTICLE.
APPLICATION FILED MAR. 18, 1918.

52,307.

Patented Aug. 27, 1918.

Inventor:
Edgar F. Curtis,
by James R. Hodder
Attorney.

UNITED STATES PATENT OFFICE.

EDGAR F. CURTIS, OF SALEM, MASSACHUSETTS, ASSIGNOR TO JOSEPH W. WOODS & SONS COMPANY, OF BOSTON, MASSACHUSETTS, A CORPORATION OF MASSACHUSETTS.

DESIGN FOR A WOVEN FABRIC OR SIMILAR ARTICLE.

52,307.

Specification for Design.

Patented Aug. 27, 1918.

Application filed March 18, 1918. Serial No. 223,245. Term of patent 7 years.

To all whom it may concern:

Be it known that I, EDGAR F. CURTIS, a citizen of the United States, residing at Salem, in the county of Essex and State of Massachusetts, have invented a new, original, and ornamental Design for Woven Fabric or Similar Article, of which the following is a specification, reference being had to the accompanying drawing, forming part hereof.

The drawing shows my design for a woven fabric which may be duplicated indefinitely.

I claim:

The ornamental design for woven fabric or similar article, as shown.

EDGAR F. CURTIS.

Witnesses:

THOS. CONNELL,
ETHEL V. STALES.
